UNITED STATES PATENT OFFICE.

LEON BALABAN, OF BERLIN-FRIEDENAU, GERMANY.

CIRCULAR WALL.

Application filed October 4, 1924. Serial No. 741,591.

To all whom it may concern:

Be it known that I, LEON BALABAN, a citizen of the German Empire, and resident of 22 Niedstrasse, Berlin-Friedenau, Germany, have invented certain new and useful Improvements in Circular Walls, of which the following is a specification.

My invention relates to improvements in annular or multicornered self-supporting exterior walls, such, for instance, as cooling towers, chimneys, and the like, the respective building structures being composed of appropriately moulded or shaped or profiled bricks or other stones and of iron reinforcing members inserted into and between said bricks or stones together with concrete which is rammed in while the bricks or stones are being walled up.

The nature of the invention consists in the features that, as regards, for instance, annular walls, chiefly moulded bricks or stones having a key-shaped longitudinal section are used, every stone consisting of a longitudinal leg or limb and of two transversely disposed arms or limbs located at one end of said leg and extending to the same side thereof and being spaced for a certain measure. These stones are set in the bond in layers in such a manner that their longitudinal portions lie alternately at the outer and the inner side of the wall, and the end of every longitudinal portion closes the space existing between the two transverse portions of the respective adjacent stone. The spaces form vertical channels in the superposed layers of the stones, and concrete combined with reinforcing iron members is rammed into said channels.

When a certain number of the horizontal layers of stones has been set, a layer of trough-shaped hollow stones is set, these stones being intended to receive a horizontal ring of reinforced concrete imbedded into the horizontal annulus formed by said trough-shaped stones.

Between the layer-joints of the longitudinal portions or legs of the first-mentioned stones bow-shaped reinforcing members are arranged; these members are connected with the reinforcing members embedded in the concrete contained in the vertical channels formed by the superposed spaces existing between the transverse portions or limbs of the said stones.

The thin longitudinal members or legs of the layers formed by the moulded stones

may be covered, if desired, with cramp-shaped or clamp-shaped hollow stones forming, together with the walls of said longitudinal portions or legs, insulating air-chambers, as is all more fully described hereinafter.

My invention is illustrated by way of example in the accompanying drawing in which Figures 1 and 2 are plans of two rows of the main stones which are to form two superposed layers; Figure 3 is a plan of a row of layer of the trough-shaped intermediate stones also mentioned in the preamble; Figure 4 is a vertical section in the plane I—I of Fig. 6, the scale being however, that of Figs. 1—3; Figure 5 is a vertical section in the plane II—II of Fig. 6, the scale being also that of Figs 1—3; Figure 6 is a horizontal section in the plane III—III of Fig. 5, drawn to an enlarged scale; and Figure 7 is a plan of a layer composed of air-chamber forming auxiliary stones and of appropriately modified main stones.

The main stones (Figs. 1 and 2) consist each of a longitudinal leg *a* and of two transverse arms *b* and *c* which are located at and near one end of said leg, are spaced for a certain measure, as shown, and extend both in the same direction, the configuration in plan of such a stone resembling, therefore, somewhat a key. These stones are set in such a manner that the legs *a* lie alternately at the outer and the inner side or surface of the wall, and the end of an outer leg close the space existing between the arms of the adjacent inner leg, and reversely (Figs. 1, 2 and 6). The horizontal direction in the superposed layers alternates also, as appears from a comparison of Figs. 1 and 2, the arms *b* and *c* being located in one layer at the right hand end of the respective stones, and in the following layer at the left hand end thereof. The arms of the stones of the several layers lie always vertically over one another and form vertical channels *d* into which are inserted the reinforcing members and is rammed the concrete enclosing, and co-operating with, these members.

e Fig. 6 denotes the reinforcing concrete cores located between the superposed arms *b* and *c* of the main stones *a b c*. The trough-shaped hollow stones *f* (Fig. 3) are open at both ends, and the consecutive stones *f* of a layer form a channel into which are inserted the horizontal reinforcing members *g* (Fig. 4) and *h* (Fig. 5) and

the concrete enclosing these members and co-operating therewith is rammed. It is suited to the purpose to make use of trough-shaped stones *f* of different breadth or width, those having the larger breadth or width being arranged between the lower layers of the main stones *a b c*, and those having the smaller breadth or width being arranged between the upper layers of the stones *a b c*, as shown in Figs. 4 and 5.

i denotes the tie-bows located in the layer of mortar between the joint-faces of the legs *a*, and *k* (Fig. 7) denotes cramp-shaped or clamp-shaped auxiliary stones by which insulating air-chambers are formed at the inner sides of the legs *a*. These auxiliary stones are used, preferably, in connection with modified main stones, the arms *b* of which being somewhat shorter than the arms *a*, as shown (Fig. 7).

I claim:

1. An annular wall structure composed of a plurality of superposed layers of blocks, said blocks each having a longitudinal leg and two transverse arms spaced apart one of which arms is located at the end of said leg and both arms being on the same side of said leg, said blocks being laid up in the wall

with the longitudinal legs alternately at the inner and outer sides of the wall; the free ends of the blocks closing the space left between the arms, said superposed arms forming continuous vertical channels, reinforcements in said channels and a filling of concrete surrounding said reinforcements. 30 35

2. An annular wall structure composed of a plurality of superposed layers of blocks, said blocks each having a longitudinal leg and two transverse arms spaced apart one of which arms is located at the end of said leg and both arms being on the same side of said leg, said blocks being laid up in the wall with the longitudinal legs alternately at the inner and outer sides of the wall; the free ends of the blocks closing the space left between the arms, said superposed arms forming continuous vertical channels. 40 45

In testimony whereof I have hereunto signed my name this 6th day of September, 1924, in the presence of two subscribing witnesses. 50

LEON BALABAN
